UNITED STATES PATENT OFFICE.

JOHN A. MOORE, OF LOUISVILLE, KENTUCKY, ASSIGNOR TO THE MENGEL COMPANY,
OF LOUISVILLE, KENTUCKY, A CORPORATION OF NEW JERSEY.

MACHINE FOR PUNCHING AND CUTTING TAPE.

1,380,492.

Specification of Letters Patent. Patented June 7, 1921.

Application filed July 21, 1917. Serial No. 182,078.

To all whom it may concern:

Be it known that I, JOHN A. MOORE, a citizen of the United States, residing at Louisville, in the county of Jefferson and State of Kentucky have invented a certain new and useful Improvement in Machines for Punching and Cutting Tape, of which the following is a specification.

My present invention pertains to an improved machine for facilitating the severance of a tape of paper or like material, preferably gummed or glued, into predetermined lengths, and for punching said tape so as to produce so-called "fish-tailed ends" upon the tape when the same is severed.

The main object of the invention is to provide a simple machine wherein the previously gummed tape may be drawn off from a reel and severed into predetermined lengths (when such lengths are desired), and to punch the tape with suitably shaped openings across which the tape may be torn or severed to produce fish-tailed ends.

A further object is to provide a carriage for the punching mechanism, which carriage is adjustable toward or from the severing device so that fish-tailed sections of predetermined lengths may be formed.

With these and other objects in view, which will appear from the following description, reference will be made to the annexed drawings, wherein:

Figure 1 is a longitudinal sectional elevation of the machine;

Fig. 2 a longitudinal sectional view;

Fig. 3 a top plan view;

Fig. 4 a view similar to Fig. 1 with the parts in different operative positions;

Fig. 5 a transverse sectional view of the punch mechanism, taken on the line V—V of Fig. 6;

Fig. 6 a sectional view taken on the line VI—VI of Fig. 5;

Fig. 7 a view similar to Fig. 6, showing the tape clamp and punch in their lowered position;

Fig. 8 a perspective view of the punch carrier;

Fig. 9 a like view of the punch;

Fig. 10 a sectional view of the carrier and

punch, illustrating the concavity of the latter;

Fig. 11 a bottom plan view of the punch;

Fig. 12 a plan view of a portion of the tape, showing the opening formed therein by the punch;

Figs. 13 and 14 sectional elevations of the clutch mechanism employed to bring the punch into operation; and

Fig. 15 a sectional view on the line XV—XV of Fig. 1, showing the control lever for the clutch, and the tape-guide and severing device.

Referring to the drawings, 1 denotes a suitable bed or table, upon which is secured a pair of L-shaped castings 2, see Figs. 3 and 5, said castings being arranged parallel to each other and extending lengthwise of the bed. At the rear end of the castings is secured a bracket 3, which forms the support for an arm 4, which carries a reel 5 for the tape, denoted by 6. The tape passes from the reel beneath a roller 7, forwardly through the punch press, in a manner to be presently described, thence beneath a roller 8, Fig. 2, through the forward guide 9, Fig. 15, and beneath the straight-edge or blade 10, against which the tape is drawn upwardly when it is desired to tear a section off. The blade 10 and guide 9 overlie a water-reservoir 11; and a roller 12, partly immersed in the water, stands immediately adjacent the blade, the glued side of the tape (as the same is drawn forwardly) contacting with said roller.

To permit the operator to readily determine the length of strip withdrawn, prior to severance, an adjustable gage is provided. In the present instance it takes the form of a pin or post 13, see Figs. 1 to 4, which extends upwardly from a slide 14 mounted for adjustment beneath the table-top. By drawing the slide out, the pin 13 will, of course, be carried farther away from the blade 10. In use, the operator draws the tape forwardly until its end abuts the post, when the tape will be drawn sharply up against the blade, thus severing the requisite length. The slide is readily adjusted and may be clamped in its adjusted position through any suitable means.

The punching mechanism is likewise located along the supporting castings 2, and is designed to punch a diamond-shaped opening, as 15, in the tape, see Fig. 12. Secured to the opposite inner faces of the castings 2 are tracks or ways 16, Fig. 5, on which is slidably mounted a carriage 17, said carriage having an upwardly-extending column 18. Mounted upon the upper face of the carriage is a die-plate 19, having an opening therein of the size and shape corresponding to that which is to be punched in the tape.

Mounted on the front face of the column 18, between guides 20 and 21, is a slide 22, the lower end of which (see Fig. 8) is recessed to receive the rib 23 on the upper face of the punch or punching die 24, which is fixedly secured in place by a screw 25. The punch in outline conforms to the opening in the die-plate, and the under face thereof is preferably slightly concave, see Fig. 10, so that the forward and rear points will first impinge upon the tape, whereby the tape is prevented from wrinkling and the cut partakes of the nature of a shearing cut from each end of the center.

To hold the tape closely to the underlying die-plate 19, a presser-plate 26 is employed. Said plate is provided with an opening through which the punch may pass and two posts 27 are threaded into the upper face thereof, said posts passing freely through openings formed in a cross-bar 28, fixed to slide 22. Nuts 29 are mounted on the upper ends of said posts, and springs 30 surround the posts, bearing at their opposite ends against the cross-bar and presser-plate, and serving to force the plate 26 downwardly. When the die is elevated (see Fig. 6) the die and presser-plate stand above and free of the tape; when, however, the slide 22 is forced downwardly, plate 26 first clamps the tape against the underlying die-plate and comes to rest and the punch continuing its downward movement passes into the die-plate and punches out the tape, as shown in Fig. 12.

Preferably a power mechanism is employed to actuate the punch, said mechanism being under the direct control of the operator.

Secured to column 18 is a bracket 31 (Fig. 5) to which is pivoted a lever 32, said lever being secured to slide 22 by an arm 33. To the outer end of lever 32 is secured a link 34, the lower end whereof is pivotally connected to the outer end of a short lever 35, having a squared opening therein, through which extends a squared shaft 36. Lever 35 is adapted to slide on shaft 36, and is movable lengthwise thereof with the punch carriage 17. To effect this sliding movement a bracket 37 is secured to the carriage and fin-

gers 38 (Figs. 1 and 5) straddle said lever 35 and shift the same along the shaft in consonance with the carriage, as it is adjusted from one position to another. Shaft 36 is sustained alongside one of the members 2 in suitable bearings 39, 40, and to the rear end 70 thereof is secured a rocker-arm 41, see Figs. 13 and 14. The outer end of the rocker-arm is pivotally connected to the upper end of a link 42, while the lower end of the link is pin-jointed to an eccentric strap 43, 75 which surrounds an eccentric 44 loose upon the constantly-driven power-shaft 45. A hub-shaped member 46 is secured to or formed integral with the eccentric and is provided with clutch teeth at its inner end. 80 The hub is provided with an annular groove in which is wound a flexible cord 47, one end of the cord being attached to the frame of the machine, while the other is secured to one end of a coiled spring 48, said spring in 85 turn being secured to the frame, see Fig. 1. This arrangement tends to draw the hub and its allied parts inwardly toward the toothed clutch element or hub 49, which is fast to the shaft. The clutch elements are 90 designed to be normally held out of engagement and to be brought into operative relation only when it is desired that the punch shall perforate the tape. To this end the hub 46 is provided with a cam face 50, and a lever 51, fulcrumed at 52, overlies the hub and is adapted (see Fig. 14) to coact with the cam face 50 and to shift the hub 46 laterally against the action of the spring-drawn or tensioned belt or cord 47, thus 95 separating the clutch elements. A spring 54 (Fig. 4) connected to the lower end of a link 55 which is also connected to the free end of lever 51, normally holds said lever against the cam face 50 and keeps the 100 clutch elements out of engagement. The upper end of link 55 is connected to one arm of a bell-crank lever 56 and a draw-rod 57 is connected to the other arm, said rod extending forwardly and being connected 110 at its forward end to one arm of a second bell-crank lever 58. A link 59, connected to the other arm of said lever, extends upwardly through an opening in the table 1 (see Fig. 15), its upper end being curved or 115 made hook-shaped and overlying one end of a control lever 60. Said lever is fulcrumed upon a fixed bracket-shaped support 61 rising from the bed or table 1. A hook-shaped limiting stop 62 is secured to said 120 support 61 and stands over the upper end of link 59, so that the lever 60 cannot be depressed too far.

With the parts in the positions shown in Figs. 1 and 2, lever 51 is held depressed and 125 the clutch elements are separated; when, however, lever 60 is depressed link 59 is drawn upwardly and through bell-crank 58,

rod 57, and bell-crank 56, link 55 is drawn upwardly against the tension of spring 54, and lever 51 is raised, withdrawing the same from engagement with cam face 50 and permitting spring 48 to tighten cord 47 and draw the clutch elements into engagement. The eccentric then partakes of the rotary motion of the driving shaft 45, link 42 being raised from the position shown in Fig. 13 to that in Fig. 14, thereby partially rotating shaft 36 and through lever 35, link 34, lever 32 and arm 33, forcing slide 22 downwardly, causing the punch 24, carried thereby to pass through the underlying tape, as shown in Fig. 7.

Upon the completion of the revolution of the eccentric, the parts will again come to their normal inactive positions, with the lever 51 bearing upon the cam face 50 and separating the clutch elements. This, of course, presupposes that the operator releases the lever 60 shortly after it is depressed, as it is only necessary that it should be moved down once to effect the punching operation for each opening formed in the tape.

The die-punching mechanism may, of course, remain inoperative, where straight-end strips of tape are to be torn off or severed. When, however, fish-tail ends are to be produced, the operator will adjust the punch carriage along its ways a distance from the blade 10 equal to the desired length of strip to be severed, the tape being drawn forwardly until the widest portion of the opening 15 alines with the blade, at which time the operator will depress lever 60 and likewise draw the tape upwardly against the blade 10. If desired, gage-pin or post 13 may be set away from the blade a distance equal to the desired length of strip, which distance, of course, will be equal to that of the distance between said blade and the center of the punch 24, thus enabling the operator to draw the tape outwardly and sever the same without the necessity of watching to see that the opening 15 therein properly registers with the severing blade.

With a machine as above set forth it has been found that an operator may readily and with rapidity withdraw the tape and sever the same and apply such moistened, severed strips to boxes, packages, or the like.

Having thus described my invention, what

I claim is:

1. In a machine for forming predetermined lengths of fish-tailed strips from a flexible tape of paper or cloth, the combination of means for holding a supply of such tape; a fixed blade beneath which the tape passes and against which it may be drawn laterally to sever the same; a gage located forward of and adjustable toward and from

the fixed blade; and a punch located to the rear of the blade and adjustable toward and from the same, said punch being so formed as to produce oppositely disposed fish-tailed ends.

2. In a machine for forming predetermined lengths of fish-tailed strips from a flexible tape of paper or cloth, the combination of a bed or table; a guideway mounted thereon; a punch mechanism embodying a fish-tailed punch supported by the guideway and adjustable longitudinally thereon; means for holding the tape in proper relation to the punch mechanism; means for actuating the punch mechanism; and a tape severing device comprising a fixed plate beneath which the tape passes and against which it may be drawn laterally to sever the same.

3. In a machine for forming predetermined lengths of fish-tailed strips from a flexible tape of paper or cloth, the combination of a bed or table; a guide-way therein; a punching mechanism mounted on the guide-way and adjustable lengthwise thereof; means for holding a flexible tape in proper relation to the punching mechanism; an actuating shaft for the punching mechanism, said shaft being coextensive of the adjustment of the punching mechanism along the guideway; a fixed blade located beyond the punching mechanism and beneath which the strip passes, said blade providing means against which the strip may be drawn to sever the same; and means for throwing the punching mechanism into operation.

4. In a machine for forming predetermined lengths of fish-tailed strips from a flexible tape of paper or cloth, the combination of means for supporting a roll of tape; a fixed blade beneath which the tape passes and against which it may be drawn laterally to sever the same, said blade being located remote from the roll of tape; a carriage adjustable toward and from said blade; a die plate mounted on the carriage and movable therewith; a die punch also mounted on the carriage and movable therewith; said die plate being diamond shaped in outline to produce a double fish-tailed opening in the tape; a presser plate coacting with the punch and adapted to press the tape against the plate; and means for actuating the punch.

5. In a machine for forming predetermined lengths of fish-tailed strips from a flexible tape of paper or cloth, the combination of means for supplying tape; a severing device comprising a fixed plate located remote from the tape supply and against which the tape may be laterally drawn to sever the same; a carriage adjustable toward and from said fixed plate; a die plate mounted on the carriage and underlying the tape; a

die punch also mounted on the carriage, said plate and die having a diamond shaped outline to produce a fish-tailed formation in the tape; a shaft extending alongside the carriage; operative connections extending from the shaft to the punch; a constantly rotating power shaft; actuating connections be-

tween the shaft and the die and punch, said connections being normally disconnected; and means under the control of the operator 10 for rendering said connections operative.

In testimony whereof I have signed my name to this specification.

JOHN A. MOORE.
